(57) **CLAIM**

The ornamental design for a golf bag top with spiral configuration, as shown and described.

DESCRIPTION

FIG. 1 is a perspective view of the golf bag top.
 FIG. 2 is a front view of the golf bag top.
 FIG. 3 is a first side view of the golf bag top.
 FIG. 4 is a second side view of the golf bag top.
 FIG. 5 is a top view of the golf bag top.
 FIG. 6 is a rear view of the golf bag top.
 FIG. 7 is an opposite direction perspective view of the golf bag top.
 FIG. 8 is an opposite direction front view of the golf bag top.
 FIG. 9 is an opposite direction first side view of the golf bag top.
 FIG. 10 is an opposite direction second side view of the golf bag top; and,
 FIG. 11 is an opposite direction rear view of the golf bag top.
 My golf bag is characterized by the spiral configuration of the club dividers and a raised pit in the rear end.
